D. VANZILE.
STEAM FEED VALVE CONTROL MECHANISM.
APPLICATION FILED MAR. 24, 1919.

Patented Aug. 3, 1920.

INVENTOR
DANIEL VANZILE,
by *J. C. Bymaef.* ATTORNEY.

UNITED STATES PATENT OFFICE.

DANIEL VANZILE, OF VREDENBURGH, ALABAMA.

STEAM-FEED-VALVE CONTROL MECHANISM.

1,348,607.

Specification of Letters Patent.

Patented Aug. 3, 1920.

Application filed March 24, 1919. Serial No. 284,713.

To all whom it may concern:

Be it known that I, DANIEL VANZILE, a citizen of the United States, residing at Vredenburgh, Alabama, have invented a 5 certain new and useful Improvement in Steam-Feed-Valve Control Mechanisms, of which the following is a full, clear, and exact description, such as will enable others skilled in the art to which it appertains to 10 make and use the same, reference being had to the accompanying drawings, forming part of this specification.

My invention relates generally to valves and more particularly to a steam feed valve 15 and control mechanism that is particularly designed for use in connection with the steam feed cylinders of saw mills.

The principal objects of my invention are, to generally improve upon and simplify the 20 construction of the existing types of the combination steam feed and exhaust valves now generally used in connection with the steam feed cylinders of saw mills; to provide a relatively simple valve which is effective 25 in controlling the supply of steam from the supply pipe to the steam feed cylinder and the exhaust of steam from the latter; to provide a steam feed valve with a valve stem which is constructed so as to effectually prevent the valve from becoming 30 loose or detached and dropping downwardly into the lower portion of the valve housing; to provide a construction wherein the valve stem has bearings near both its ends in the 35 valve housing, thereby insuring proper movement of said valve stem and the valve carried thereby under all conditions; to provide a valve which comprises relatively few parts and which are constructed so as to be 40 readily assembled or taken apart, thereby facilitating installation and repairs; and further, to provide a simple and efficient actuating and control mechanism for the 45 two valves utilized adjacent to the ends of the steam feed cylinder of a saw mill or the like.

With the foregoing and other objects in view, my invention consists in certain novel features of construction and arrangement of 50 parts, hereinafter more fully described and claimed, and illustrated in the accompanying drawings, in which—

Figure 1 is an elevational view partly in section of a portion of a steam feed cylinder 55 for saw mills and showing my improved

valves and valve control mechanism associated therewith.

Fig. 2 is an enlarged vertical section taken approximately on the line 2—2 of Fig. 1.

Fig. 3 is a horizontal section taken approximately on the line 3—3 of Fig. 2.

Referring by numerals to the accompanying drawings, 10 designates the steam feed cylinder usually employed for operating saw mill carriages and connected to both 60 ends of this cylinder are pipes 11 which are for the purpose of conveying live steam to said cylinder and exhaust steam therefrom.

One of my improved valves and its housing is connected to each pipe 11 and each 70 housing comprises an upper part 12 and a lower part 13. The upper part 12 is in the form of a vertically disposed cylindrical body in which is formed a valve chamber 14, having the same internal diameter 75 throughout its length. Connected to one side of this upper portion of the valve body and preferably by means of a flange 15 is a branch pipe 16, which leads from a steam supply pipe 17, the latter being preferably 80 arranged at a point midway between the two valves and valve housings.

Connected to the opposite side of the valve body 12, preferably by means of a flange 18, 85 is the lower end of the pipe 11 that leads to feed cylinder 10. Formed through the wall of the housing 12 and directly opposite the point to which steam supply pipe 16 is connected, are one or more ports 19, and formed through the opposite portion of the 90 wall of the housing is a port 20, the same establishing communication between the valve chamber 14 and the pipe 11 which leads to cylinder 10.

The lower part 13 of the valve housing 95 is in the form of an elbow, the upper end of the vertical portion of which is directly connected in any suitable manner to the lower end of the upper part 12 of the housing and the end of the horizontal portion of 100 said elbow 13 is connected in any suitable manner to a branch pipe 21, which leads to an exhaust pipe 22, the latter being preferably located at a point midway between the 105 two valves and their housings.

Removably positioned on top of the upper part 12 of the housing is a head or cap 23, and arranged in the center thereof is a valve stem bearing 24 which includes a stuffing box and gland.

Formed through the lower portion of elbow 13 is a valve stem bearing 25 the same being in direct alinement with bearing 24 and said bearing 25 including a stuffing box and gland.

Arranged for sliding movement through the bearings 24 and 25 is a rod 26 which constitutes a valve stem, the upper portion thereof being smaller in diameter than the 10 lower portion, and formed integral with or fixed to said stem at a point near its center is an annular rib or flange 27. Positioned on the valve stem immediately above this rib or flange and supported thereby is a cylindrical valve body 28, the external diameter of which is such that it fits snugly within and slides freely through the chamber 14 in housing 12. Formed in the periphery of this valve body and at a point near its center 15 is an annular groove 29 which, when the valve is properly positioned, serves to establish communication between the ports 19 and 20. (See Fig. 2.) This valve is retained in position on the valve stem by means of nuts 20 30, the same being seated on a threaded portion 31 of the valve stem and bearing directly on top of said valve.

Formed through the valve member 28 near its center is a series of openings 32 30 which establish communication between the upper and lower portions of the valve chamber 14. This construction permits steam to pass upwardly through the valve to the upper portion of chamber 14, thereby equalizing 35 the pressure on both sides of said valve.

Formed integral with or fixed to the lower portion of member 12 of the housing and projecting a short distance into chamber 14 are lugs 33 which perform the functions of 40 stops to limit the downward movement of valve 28 in valve chamber 14. Arranged immediately to the side of each valve housing is an upright member 34, and journaled in the ends thereof are groove pulleys 35.

Arranged for operation on the upper pair 45 of these pulleys is a flexible member such as a cable or chain 36, the ends thereof being connected in any suitable manner to the upper ends of the valve stems 26. A similar 50 cable or chain 37 passes beneath the lower pair of pulleys 35 and the ends of the last mentioned cable are suitably connected to the lower ends of the valve stems.

Fulcrumed upon a fixed bracket 38 is a 55 lever 39, the ends thereof being connected in any suitable manner to the cables 36 and 37 and connected to the upper ends of this lever is one end of a rod or like operating member 40, the other end being connected 60 to a lever 41 and which latter is manipulated by the sawyer.

The operation of my improved cable and control mechanism is as follows:

It will be noted that both ends of both 65 valve stems are connected by the cables 36

and 37. Consequently, when one valve stem and valve carried thereby is moving downward, the other valve stem will be elevated, and thus as one valve is opened to admit steam to the corresponding end of cylinder 70 10, the other valve will be closed or shifted from steam feeding position to its exhaust position to permit the exhaust steam to escape into exhaust pipe 22.

The valves are actuated by manipulation 75 of the lever 41 and through connecting rod 40, the movement of said lever is transmitted to the cables 36 and 37 and from thence to the valve stems.

The steam feeding position of the valve is 80 illustrated by solid lines in Fig. 2, and when so positioned, live steam passes from pipe 16 through port 19, from thence through the groove 29 around the periphery of the valve and from thence through port 20 to pipe 11 85 connected thereto, and through said pipe to cylinder 10. The steam thus entering cylinder 10 will move the piston therein through said cylinder and the exhaust steam from said cylinder will pass through the opposite 90 pipe 11, from thence to and through port 20 and the opposite valve housing, and thence downwardly beneath the valve in said housing, and which latter valve is elevated as shown by dotted lines in Fig. 2, and said 95 steam will pass outwardly through elbow 13 and the branch exhaust pipe 21 connected thereto. Thus, both valves are simultaneously operated and through their operation steam is alternately admitted to the 100 ends of the feed cylinder 10 to actuate the piston therein, and consequently impart proper movement to the carriage or part connected to said piston and its rod.

The valve stem 26 has bearings in both 105 ends of the valve housing, and, therefore, said valve stem always maintains its proper operative position and the valve 28 seated upon the rib or flange 27 is effectually prevented from dropping downward in the 110 valve housing and which result very frequently occurs where the valve stem terminates immediately below the valve and the latter is held on the stem by nuts or the like.

A steam feed valve and control mechanism 115 of my improved construction is comparatively simple, is positive in operation, and is very effective in performing its intended functions.

It will be readily understood that minor 120 changes in the size, form and construction of the various parts of my improved device may be made and substituted for those herein shown and described, without departing from the spirit of my invention, the scope 125 of which is set forth in the appended claim.

I claim:

In combination with a steam feed cylinder, pipes connected to the ends thereof, valve housings connected to said pipes, a 130

steam supply pipe connected to both valve housings, exhaust pipes leading from said housings, each housing being provided with a valve chamber, a valve stem arranged for 5 operation in each housing, a valve carried by each stem for controlling the passage of steam through the valve housing, cables connecting the adjacent ends of both valve stems, pulleys over which said cables are 10 adapted to pass, a lever fulcrumed interme-

diate its ends, said ends being connected to an adjacent cable, an operating lever spaced apart from the first-mentioned lever, and a rod connecting the lower end of the operating lever with the upper end of the first- 15 mentioned lever.

In testimony whereof I hereunto affix my signature this 18th day of March, 1919.

DANIEL VANZILE.
